COLLAPSIBLE POLE AND ROD HOLDER

Filed May 20, 1929

ARTHUR F. GEISINGER
INVENTOR.

BY
Arthur P. Woolfolk
ATTORNEY.

UNITED STATES PATENT OFFICE

ARTHUR F. GEISINGER, OF MILWAUKEE, WISCONSIN

COLLAPSIBLE POLE AND ROD HOLDER

Application filed May 20, 1929. Serial No. 364,563.

This invention relates to a pole and rod holder, and objects of this invention are to provide a collapsible pole and rod holder which may be collapsed or folded into a very compact form so that it may be readily stored in a small space, and which is so made that it may be readily adjusted to its pole receiving position with the utmost facility.

Further objects of this invention are to provide a novel form of pole and rod holder which is so constructed that it may be clamped to the seat of a boat or other support and may project at any desired angle from the clamping means, which is adjustable to vary the angle at which the pole is held, and which is provided with pole-receiving saddles which are pivotally mounted and are adapted to permit the ready and free insertion of the pole but which, when an attempt is made to withdraw the pole, rock into a position tending to further grip the pole and prevent its inadvertent removal.

An embodiment of the invention is shown in the accompanying drawings, in which:

25 Figure 1 is a plan view of the rod holder showing the parts in their collapsed or folded positions.

Figure 2 is a side elevation of the structure shown in Figure 1.

30 Figure 3 is a side elevation showing the position of the parts when they are adjusted to receive a pole, such view showing in dotted lines a further adjustment to vary the angular setting of the pole.

35 Figure 4 is a fragmentary bottom view partly in section showing the pivoted end of the main frame and the adjacent parts.

Referring to the drawings, it will be seen that a body portion or supporting frame 5 has been shown as of rectangular construction and provided with inwardly turned rear ends. These inwardly turned rear ends are pivotally joined to a pivot block 7 by means of rivets or other members 6, as shown most clearly in Figure 4. This pivot block is of downwardly opening, channel shape, as may be seen from Figure 4, and has its outer flanges located outside of the rear ends of the main frame 5. The construction is such that when the pivot block is rocked into operative

position, as shown in Figure 3, it bears against the upper side of the main frame member 5. This pivot block is provided with a downwardly extending tongue 8 to increase its stiffness. The pivot block 7 is secured to any suitable form of clamp, so that the pivot block and, consequently, the body portion or main supporting frame 5, may be locked to any desired support, for instance, the seat of a boat. Preferably, the pivot block 7 is pivotally joined to the clamp as indicated at 9 in Figures 3 and 4, so that the body portion or main frame 5 may be set at any desired angle.

A pair of supporting levers 10, which constitute a supporting frame, are pivoted at 11 to the main frame 5 and may, if desired, be curved, or, obviously, they may take other shapes provided they are adapted to be adjusted into the positions shown at Figure 3 or folded into the position shown in Figures 1 and 2. These supporting arms or levers 10 are provided with a supporting strut or frame 13 which is pivotally joined as indicated at 12 to the outer ends of the pivoted arms 10. The supporting frame 13 may take different forms, but it is preferably relatively rigid to withstand the weight of the rod when the rod is positioned as will hereinafter appear.

An outer or front supporting saddle 20 has its ends pivoted to the arms 10, preferably by means of the rivets or pivot members 12, and in operative position projects generally downwardly from the outer ends of the arms. At a point adjacent the rear ends of the pivoted arms 10 a rear saddle 19 is secured by means of rivets or pivot members 21. This rear saddle 19 projects generally upwardly when the device is in use.

The body portion is provided with notches 16, 17, and 18 on opposite sides, and the lower end of the supporting strut or brace 13 is adapted to be received in any aligning pair of these notches. Preferably the lower corner portions of the supporting member 13 are notched out as shown at 14 and 15.

In using the device the body portion or main frame 5 is placed upon a suitable support, such as the seat of a boat, and is

clamped in place after being pointed in the proper direction, the frame freely pivoting about the rivet 9 and allowing any desired direction to be given the pole. Thereafter 5 the vertical angle at which the pole is set may be determined by fitting the lower end of the strut 13 into the appropriate notch of the series of notches 16, 17, and 18. The rear end of the pole rests against the rear 10 part of the frame and the adjacent part of the pivot block 7. Very clearly the pole is very securely held by this device. It is preferable to form the forward saddle of approximately V-shape, as shown most clearly 15 in Figure 1, so that somewhat of a gripping action upon the pole is inherently secured.

If a sudden pull is imparted to the pole through the medium of the line, as, for example, 20 when the device is used for holding fishing poles, it is obvious that this pull will be somewhat downwardly and will cause the pole to bind tightly against the forward saddle 20, its rear end bearing upwardly against the saddle 19 and increasing the frictional 25 engagement therewith. If this pull is also somewhat forwardly, it is apparent that the saddles 19 and 20 will rock slightly and will secure an even better grip upon the pole, as 30 they tend to clinch to the pole.

This action has been found to take place from actual trials of the device.

The pole cannot slip rearwardly as it abuts against the rear portion of the device, for 35 example, the rear portion of the frame or the pivot block 7.

The apparatus may be very readily folded into compact form, as shown in Figures 1 and 2, by rocking the rear saddle forwardly 40 and the front saddle rearwardly, and rocking the strut 13 completely around the end of the arms 10 so that it lies upon the upper side of the arms. Thereafter the arms 10 are folded or rocked downwardly as shown 45 in Figures 1 and 2. The pivot block permits the forward rocking of the clamp into or towards the under side of the apparatus, so that it will occupy the position shown in Figures 1 and 2, thus permitting the apparatus 50 to fold into a very compact form.

Although the rod is held against downward or forward motion, it nevertheless may be instantly detached by merely rocking the rod upwardly and withdrawing it from the 55 device. Thus, when it is necessary for the fisherman to quickly remove the rod, this operation is most readily permitted.

Although the invention has been described in considerable detail, it is intended that 60 this description be interpreted as illustrative rather than limiting, as the invention may be variously embodied and is to be interpreted as claimed.

What I claim as my invention:

55 1. A rod holder comprising a main frame,

a pair of forwardly projecting arms pivoted thereto, a forward saddle carried by the forward end of said arms, a rear saddle carried by the rear portion of said arms, said saddles being adapted to receive a pole, and 70 means pivoted to said arms and adapted to engage said main frame at any one of a plurality of points to vary the angular setting of said arms.

2. A rod holder comprising a main frame, 75 clamping means for clamping said frame to a suitable support, said clamping means being joined to said main frame through the medium of two pivots at right angles to each other, a frame pivoted to said main frame 80 and adapted to be rocked upwardly and having a downwardly looped forward saddle and an upwardly looped rear saddle adapted to receive a rod, the rear end of said rod being adapted to bear against the rear portion of the rod holder, whereby a rearward motion of the rod is prevented, and means for varying the angular setting of said second mentioned frame.

3. A rod holder comprising a main frame 90 having notched side portions and having a pivoted member at its rear portion, a clamp secured to said pivoted member and adapted to be folded upwardly towards said main frame, a pair of arms having their rear ends 95 pivotally joined to said main frame, a supporting strut pivoted to said arms and adapted to be seated in any one of the notches in said main frame, and a forward and a rear saddle carried by said arms and 100 adapted to receive a rod, said arms, said saddles, and said strut being foldable with reference to said main frame.

4. A rod holder comprising a main frame of roughly rectangular contour having 105 notched side portions, means for securing said frame to a support, a pair of arms having their rear portions pivoted to said main frame, a rear saddle and a forward saddle pivoted to said arms and adapted to receive 110 a rod, and a strut pivoted to said arms and having a lower portion adapted to enter any one of said notches.

In testimony whereof I affix my signature,

ARTHUR F. GEISINGER.
